BRIDGE CONSTRUCTION FOR PIGGYBACK FLAT CARS

Earl L. Thompson, Chicago, Ill., assignor to Pullman Incorporated, Chicago, Ill., a corporation of Delaware
Filed Dec. 31, 1962, Ser. No. 248,460
1 Claim. (Cl. 105—458)

This invention relates to piggyback flat cars of the type having increased travel cushioning means associated therewith and more particularly to a bridge construction adapting such a flat car for piggyback loading with conventional flat cars.

Piggyback flat cars have found widespread acceptance in the railroad industry. These cars are flat cars employed for transporting by rail highway vehicles such as tractor trailers and the like. The conventional method of loading piggyback flat cars consists of first arranging a series of such cars on a siding, and then driving each tractor trailer over a series of flat cars to its desired position. Bridge construction is provided between adjacent ends of the flat cars, and it conventionally includes a pair of steel bridge plates each pivoted to one of the flat cars and swingable between a horizontal loading position spanning the space between the cars and a vertical transit position for transport.

With the perfection of shock dissipating cushioning means for railway cars, many piggyback flat cars now being manufactured include such cushioning means, and many existing flat cars are being modified to incorporate shock dissipating cushioning means. Cushioning means for flat cars quite often includes a sliding sill type cushioning arrangement which basically includes a longitudinally continuous sill stricture slidably received in a box-like center sill in the underframe of the flat car, which continuous sill has couplers mounted at the opposite ends thereof. A suitable hydraulic or other type of cushion operatively interconnects the sliding sill with the underframe of the car. When such a flat car receives an operational shock in buff or draft, the cushioning arrangement absorbs substantially all of the shock which results in relative longitudinal movement between the sliding sill and the underframe of the flat car. In order to accommodate this movement of the sliding sill it has been necessary to space the couplers at the ends of the sliding sill for a substantial distance beyond the ends of the flat car.

The use of piggyback flat cars having shock dissipating cushioning means associated therewith has presented problems in the loading of these flat cars by the method described above. Because these flat cars have the couplers thereof spaced a substantial distance beyond the ends of the flat car, when one of these piggyback flat cars is coupled with a piggyback flat car of conventional design, it has not been possible to bridge the increased distance between these two cars with the bridge plates furnished with the cars. This is due to the fact that the bridge plate on the conventional flat car is not long enough to span the distance between the conventional flat car and the flat car having the cushioning means associated therewith.

In addition to the above mentioned problem of piggyback loading which is brought about by the use of flat cars having shock dissipating cushioning means, the same problem is quite often presented when coupling piggyback flat cars wherein none of the cars have the above described shock dissipating means associated therewith. This may occur with the coupling of flat cars having couplers of varying lengths or having couplers with conventional rubber pad cushioning means but with varying lengths of travel. In any case the result will be a greater

2

space between adjacent end sills of the coupled cars, which space will be too great for spanning by a bridge plate of one of the cars.

Accordingly, it is a primary object of the present invention to provide in a piggyback flat car of the type having increased travel cushioning means associated therewith a bridge construction adapting such a car for piggyback loading with a conventional flat car.

It is a further object of the present invention to provide in a piggyback flat car of the type described a bridge plate and a bridge plate support at each end of the car adapting the same for piggyback loading with flat cars of varying coupler length.

It is an even further object of the present invention to provide in a piggyback flat car of the type having relatively long travel cushioning means a bridge plate and a bridge plate support at each end of the flat car adapting the same for piggyback loading with a conventional flat car, which bridge plates and which bridge plate supports are adapted to be swung from a loading position to a transit position.

It is a more specific object of the present invention to provide in a piggyback flat car of extended coupler length a new bridge plate support adapted to support the free end of the bridge plate of a flat car of shorter coupler length coupled with the first mentioned flat car, which bridge plate support is adapted to be pivoted to a transit position when it is not in use.

It is a still further object of the present invention to provide in a piggyback flat car having an extended coupling projection a new bridge plate support pivotally mounted at each end of the sill of such flat car, which bridge plate support is constructed to accommodate conventional bridge plate equipment of conventional flat car design.

It is an even further object of the present invention to provide in a more extensively cushioned piggyback flat car of the type described a new bridge plate support pivotally mounted adjacent each end sill of such a flat car, which support is adapted to support the free end of the bridge plate of a conventional flat car coupled with the first mentioned flat car and which support is reinforced to accommodate the laterally spaced loads of dual wheel tractor trailers.

These and other objects and advantages of the present invention will become apparent from the following specification wherein like numerals refer to similar parts throughout.

In the drawings:

FIG. 1 is a fragmentary top plan view of adjacent ends of coupled piggyback flat cars, one of which flat cars has shock dissipating cushioning means associated therewith;

FIG. 2 is a section taken along the line 2—2 of FIG. 1 with certain parts of the flat cars being removed or fragmentarily shown to illustrate the bridge construction more clearly;

FIG. 3 is a section similar to FIG. 2 but showing parts of the bridge construction in the transit position;

FIG. 4 is an enlarged top plan view of the bridge plate support of this invention with a part of the same being broken away and showing the support in the loading position thereof;

FIG. 5 is an elevation of the bridge plate support as seen from one end of a piggyback flat car with a part of the support being broken away and showing the same in the loading position thereof;

FIG. 6 is a section taken along the line 6—6 of FIG. 4;

FIG. 7 is a section taken along the line 7—7 of FIG. 4;

FIG. 8 is a section taken along the line 8—8 of FIG. 4; and

FIG. 9 is a section taken along the line 9—9 of FIG. 4.

As best seen in FIG. 1, a piggyback flat car having shock dissipating cushioning means associated therewith is generally designated 10, which flat car includes a bed or deck 11, an end sill 12 and side sills 13 and 14. One end of a longitudinally continuous sliding sill 15 is shown, which sill includes an outwardly flared coupler housing 16 terminating at a striker plate 17. A railway car coupler 18 is pivotally mounted in the conventional manner within the housing 16 and secured to one end of the sill 15. It will be understood that the longitudinally continuous sill 15 extends for the entire length of the flat car 10 and is suitably slidably received in a box-like center sill 19, which box-like center sill is rigidly secured as a part of the underframe structure of the flat car. It will be further understood that a hydraulic or other type cushion, such as that shown in United States Patent No. 3,003,436, operatively interconnects the sill 15 with the underframe of the flat car 10. Operational shocks in buff or draft applied to the couplers of the flat car 10 are absorbed by the cushioning means which results in relative movement between the sill 15 and the car 10. Such relative movement can be on the order of 20 to 40 inches in either direction as set forth in the aforementioned patent. To accommodate this relative movement the opposite ends of the sill 15, and accordingly the couplers secured thereto, are spaced a substantial distance from the end sills of the flat car 10.

FIG. 1 also fragmentarily shows a conventional piggyback flat car generally designated 20, which flat car includes a deck or bed 21, an end sill 22 and side sills 23 and 24. Rigidly secured to the underside of the flat car 20 is a coupler housing 25, which coupler housing includes a striker plate 26. A railway car coupler 27 is pivotally mounted to the flat car 20 within the housing 25 in a conventional manner. The piggyback flat car 20 does not have long travel shock dissipating cushioning means associated therewith; hence, the close spacing between the coupler 27 and the end sill 22 of the flat car 20. The coupler 27 is connected to the car 20 by means of any suitable type of draft gear means including a rubber pad cushioning arrangement (not shown) providing for conventional gear travel of about 2½ to 3 inches.

The flat car 20 is provided with a bridge plate 28 of conventional design, which bridge plate is pivotally mounted at one end of the flat car at a corner thereof in line with one longitudinal side or wheel track area of the deck 21 for swinging movement between a generally horizontal loading position and a generally vertical transit position. The opposite end of the car includes a similar bridge plate aligned with the opposite longitudinal side or wheel track area of the deck 21. Each bridge plate 28 is provided along one side thereof with a grab iron 29, and the bridge plate is provided along the other side thereof with a locking pin 30, which locking pin is adapted to have one end thereof received through an opening 31 in the deck of the flat car 20 for engagement with a suitable socket for supporting the bridge plate 25 in the transit position.

The bridge construction for the piggyback flat car 10 is the same at both ends thereof. Accordingly, it will suffice to describe the bridge construction at only one end of the flat car 10. A bridge plate 35 is pivotally mounted on the deck 11 at one end of the flat car 10 for swinging movement between a generally horizontal loading position and a generally vertical transit position. The bridge plate 35 is of a greater length than the length of the conventional bridge plate 28 thereby adapting the bridge plate 35 to span the increased distance between the end sills 12 and 22 of the piggyback flat cars 10 and 20, respectively. The bridge plate 35 is provided with a grab iron 36 along one side thereof and with a locking pin 37 along the other side thereof. When the bridge plate 35 is in the vertical or transit position, the lower end of the locking pin 37 is adapted to be received

through an opening 38 in the deck 11 of the flat car 10 where it will be received in a suitable socket for supporting the bridge plate in the transit position.

As seen in FIGS. 1 and 2, the bridge plate 28 of conventional design is not of sufficient length to span the distance between adjacent end sills 12 and 22 of the two piggyback flat cars because of the increased distance between these two end sills. As mentioned above, this increased spacing is due to the mounting of the coupler 18 a substantial distance from the end sill 12 of the piggyback flat car 10 because of the incorporation of a long travel shock dissipating cushioning arrangement in the flat car 10. The novel means associated with the piggyback flat car 10 for supporting the free end of the bridge plate 28 of the conventional flat car 20 thereby adapting the piggyback flat car 10 for piggyback loading will now be described.

Briefly, and by way of introduction, the bridge plate support includes an elongated frame structure pivotally mounted to the deck of a piggyback flat car adjacent an end of the end sill of the flat car. The bridge plate support, which extends transversely of the piggyback flat car, is adapted to swing from a loading position wherein the support projects from the end sill of the flat car to a transit position wherein the support rests on the deck of the flat car. It will be understood that when the support is in the loading position it will project beyond the end sill of the piggyback flat car for a distance sufficient to receive the free end of the bridge plate of a conventional flat car which is coupled with the flat car having the bridge plate support. The bridge plate support is braced in the loading position by means of a stop member which is a part of the support, the stop member being adapted to abut the end sill of the flat car for transferring a portion of the load received by the bridge support to the end sill. As is known to those skilled in the art, most flat cars are provided with a pair of grab rails at each end thereof to assist workmen working around the flat car. Since the bridge plate support abuts the end sill of the flat car in the vicinity of one of these grab rails, the bridge plate support is specially constructed so as to accommodate a grab rail when the bridge plate support is in its loading position. Further, the bridge plate support is reinforced at opposite ends thereof for receiving laterally spaced loads from the dual wheels of highway tractor trailers.

Referring now to the drawings and especially to FIGS. 4 through 9, the bridge plate support, generally designated 40, is pivotally mounted to the deck 11 of the piggyback flat car 10 at a corner thereof adjacent the end sill 12. The bridge plate support, which is preferably a fabricated welded structural steel assembly, includes a flat deck plate 41 having an ear plate 42 welded at each end thereof. Each ear plate 42 is mounted between a pair of ear plates 43, which ear plates 43 are welded to the deck 11 of the flat car 10. All of the ear plates are provided with suitable bores, which are adapted to be aligned for receiving pins 44. It will be apparent that by provision of the ear plates and pins the bridge plate support is adapted to swing about a horizontal transverse axis extending through the centers of the pins 44.

The bridge plate support 40 further includes a channel member 45, which channel member has the flanges thereof extending toward the end sill of the flat car with the uppermost flange being secured to the underside of the deck plate 41 at the outer side edge thereof. The bridge plate support is reinforced at each end thereof by a pair of end plates, which end plates extend laterally of the elongated bridge support. Proceeding from left to right as seen in FIGS. 4 and 5, a first generally rectangular end plate 48 adapted to be abutted by the outer end of the channel member 45 is secured to the underside of the deck plate 41 closely adjacent the end thereof. A second generally rectangular end plate 49 spaced a short

distance from the plate 48 is secured to the underside of the deck plate 41. One end of the end plate 49 has portions thereof cut away to accommodate the shape of the channel 45. An end plate 50 of special shape is secured to the underside of the deck plate 41 near the inner end thereof, which plate 50 has an outer portion configured to accommodate the channel member 45. The plate 50 includes a depending portion which extends downwardly for a distance preferably greater than the height of the web of the channel member. An end plate 51 also of special shape is secured to the underside of the deck plate 41 adjacent the inner end thereof, which end plate is adapted to be abutted by the inner end of the channel 45. The plate 51 includes a depending portion which extends downwardly for the same distance as the depending portion of the plate 50. The end plates 48 through 51 are spaced along the underside of the deck plate 41 as illustrated in FIGS. 4 and 5 for two reasons. One, the end plates are concentrated near the ends of the deck plate 41 in the areas where laterally spaced concentrated loads from the dual wheels of highway tractor trailers will be received. Secondly, the end plates 49 and 50 are spaced apart for accommodating a standard grab rail 53, which grab rail is secured at the ends thereof to the end sill 12 of the piggyback flat car 10 in a conventional manner.

A plate 54 extending at a right angle from the deck plate 41 on the underside thereof is secured to the inner edges of the end plates 48 and 49. Preferably, a pad plate 55 is secured to the end sill 12, which pad 55 is adapted to be in substantial co-extensive contact with the plate 54 when the bridge plate support is in the loading position thereof as best seen in FIGS. 6 and 7. A vertically elongated plate 56 extends at a right angle from the underside of the deck plate 41 and is secured to the inner edges of the end plates 50 and 51. Preferably, a pad plate 57 of generally the same size and shape as the plate 56 is secured to the end sill 12, which pad 57 is adapted to be substantial co-existent contact with the plate 56 when the bridge plate support is in the loading position thereof as seen in FIGS. 8 and 9. The depending portions of the end plates 50 and 51 as well as the vertically elongated plate 56 define a stop member for limiting swinging movement of the support end for bracing the support 40 when the same is in its loading position.

When the bridge plate support 40 is swung to the loading position thereof, the flat deck plate 41 will project generally horizontally from the end sill of the piggyback flat car for receiving and supporting the free end of the bridge plate of a conventional flat car coupled with the flat car having the bridge plate support. The deck plate 41 is firmly supported in place by the combined action of the ear plates 42 secured by the pins 44 and by the action of the stop plates 54 and 56 engaging the pads 55 and 57, respectively. It will be apparent that by this construction the bridge plate support 40 will firmly support the free end of a bridge plate resting on the support. The bridge plate support is further aided in supporting a bridge plate and the moving loads to which the bridge plate may be subjected, by the provision of the depending portions of the end plates 50 and 51 and by the vertically elongated plate 56, as these parts brace the bridge plate support and transmit a portion of the vertical loads applied to the support to the end sill.

As best seen in FIG. 2, it will be noticed that when the bridge plate support is in the loading position thereof and contacted by the free end of the bridge plate 28, the bridge plate support will permit wheeled lading, such as highway tractor trailers, to pass easily between the deck of the flat car and the bridge plate or vice versa. It will be further observed that the hinge structure permitting pivoting or swinging movement of the bridge plate support is mounted at the extreme ends of the

deck plate 41 so as not to interfere with the movement of dual wheels over the bridge plate support.

Thus it will be seen that by this invention a bridge plate support has been provided for use with a piggyback flat car of the type having a long travel shock dissipating cushioning arrangement, which bridge plate support is adapted to receive and support the free end of the bridge plate of a conventional piggyback flat car coupled with the first mentioned flat car, thereby adapting the piggyback flat car having the cushioning means for directly coupled use with the conventional car during piggyback loading and unloading. As indicated above, it will be realized that the bridge plate support arrangement may be used on flat cars other than those having the sliding sill type shock dissipating cushioning means associated therewith. The support will have utility on any piggyback flat car wherein the couplers thereof are spaced more than the usual distance from the ends of the car regardless of the reason for mounting the couplers this increased distance. For example, an increase in coupler projection may be as a result of an increase in travel in draft gear design, such as a travel of 8 inches as compared to the conventional 2½ to 3 inches. The present invention also permits wider latitude in coupler and coupler mounting designs as any portion or all of the available support surface provided by the bridge plate support arrangement can be used to a varying degree. The bridge plate support is a strong and rigid structure adapting it to give firm support to a bridge plate for carrying extremely heavy loads. The support is re-enforced at the ends thereof for receiving the laterally spaced loads of a dual wheeled highway vehicle, and the bridge plate support is so constructed that when in the loading position thereof it will accommodate a grab rail mounted at the end sill of a flat car. The bridge plate support is pivotally or swingably mounted to the flat car so that it may be swung to an out-of-the-way or transit position when not in use.

While the invention has been shown in but one form it will be obvious to those skilled in the art that it is not to be so limited, but on the contrary it is susceptible to various changes and modifications without departing from the spirit and scope of the appended claim.

I claim:

1. In a piggyback flat car of the type characterized by couplers adapted for longitudinal movement with respect to the deck portion of the flat car, which couplers project a substantial distance from the ends of the flat car to accommodate such movement, the provision of bridge construction associated with at least one end of said flat car adapting the same for piggyback loading comprising, a bridge plate mounted on the deck portion of said flat car at said one end thereof and on one side of the longitudinal centerline of the car for swinging movement about a horizontal transverse axis between a generally vertical transit position and a generally horizontal loading position, which bridge plate has a length substantially greater than the distance the coupler projects from said one end of the car therefrom adapting the same to be supported at the free end thereof by a second flat car coupled at said one end of the first mentioned flat car, a separate bridge plate support disposed laterally of said bridge plate, which support comprises a transversely elongated frame structure having hinge means at each end thereof pivotally mounting the same on the deck portion of the first mentioned flat car at said one end thereof and on the other side of said centerline, said support being adapted to swing about a horizontal transverse axis between a loading position wherein the support extends beyond the end sill at said one end of the first mentioned flat car to constitute an extension of said deck portion and a transit position wherein the support rests on the deck portion of the first mentioned flat car, said frame structure comprising, a

deck plate, which deck plate lies in a horizontal plane when said support is in the loading position thereof, a transversely extending structural member secured to the underside of said deck plate at the marginal portion thereof remote from said end sill, at least one end plate at each end of said frame structure, each of said end plates extending laterally of the frame structure and being secured to the underside of said deck plate and to said structural member, said end plates being spaced apart to accommodate a grab rail mounted on said end sill when said support is in the loading position thereof, the innermost of said end plates having the depending portion, which portion has a pad secured to one edge thereof, said pad abutting said end sill when said support

is in a loading position thereof for maintaining said deck plate in a horizontal plate when the support is subjected to a load.
